Attorney.

UNITED STATES PATENT OFFICE.

NORMAN LEA, OF STRAND, LONDON, ENGLAND.

ELECTRIC COUPLING DEVICE FOR THERMIONIC VALVES.

Application filed March 3, 1926, Serial No. 92,028, and in Great Britain June 26, 1924.

The present invention relates to the construction of a coupling device for use between valves of an amplifier. The coupling device provides for what is commonly known as "resistance capacity coupling", in which variations of potential developing across a resistance in the output circuit of one valve are transferred to the control electrode of the next valve by means of a condenser, the 10 said control electrode being maintained at some convenient mean potential by means of a second and usually higher resistance connected between it and the filament or source of electrons.

15 The device therefore consists of three elements—namely, two resistances and a capacity. The combination of these three elements is in itself well known, but in order to obtain the most satisfactory results it 20 is important that they shall be arranged in a suitable manner, and the present invention concerns methods of arrangement and construction.

According to this invention the two resistances are arranged concentrically. One 25 resistance, which is connected to the output of the earlier valve and will be called "the anode resistance", consists of insulated wire wound on a tubular bobbin, and the other 30 resistance, which is connected to the control electrode of the later valve and will be called the "grid resistance", is housed inside the tubular bobbin, and the said grid resistance may comprise a partially carbonized cellulose or like thread or may be of other 35 convenient form. Each resistance has its terminals at opposite ends of the tubular bobbin, the terminals at one end being convenient for connection to the coupling condenser and to the appropriate valve electrodes.

In order to render the performance of the device sensibly independent of frequency, it 40 is preferable to have the anode resistance free, as far as possible, from self-capacity and self-inductance. Self-inductance can be reduced by employing a bifilar winding well known in electrical measuring apparatus, but this would introduce self-capacity and also insulation difficulties. Accordingly I may incorporate an anode resistance 45 consisting of wire wound in grooves on the tubular bobbin, the winding being alternately clockwise and anti-clockwise in the several grooves. In this way good insula-

tion, small self-capacity and small self-inductance are obtained.

In the accompanying drawing illustrating one embodiment of this invention, Fig. 1 is a sectional elevation and Fig. 2 is a plan. 60

Referring to Fig. 1. An anode resistance bobbin 1 has four grooves for the winding and two extra grooves, one at each end, for the purpose of making satisfactory end connections. The wire winding of the anode 65 resistance 21 is wound clockwise and anti-clockwise in alternate grooves and the ends soldered to the tag 16 and the pin 7. The grid resistance 2 of cartridge type with metal ends, is housed within the bobbin 1 70 and is held in position by the clip 10 and the spring 9. The grid resistance 2 makes metallic contact with the terminal 4 via the screw 11 and the clip 10 at the upper end and at the lower end is connected to the 75 plate 6 via the spring 9 and the screw 8. The screw 11 is used as a fixing for the terminal 4. The clip 10 pivots on the screw 11 and has its end, which engages with the conical cap of grid resistance 2, shaped as 80 in Fig. 2, so that the grid resistance may be removed or inserted by turning the clip 10, but so that the clip is locked by the upward thrust imposed by the spring 9 on the grid resistance 2.

The upper end of the anode resistance is 85 soldered to the tag 16, which is clamped by the terminal nut 18. The terminal screw 19 has a knurled head and is inserted from the opposite side of the bobbin 1 before the 90 terminal 4 and screw 11 are in place. The two plates 5 and 6 which connect the anode and grid resistances respectively to the terminals 12 and 13 of the condenser 17, which is housed in the case 14, are riveted to an 95 insulator 15. The screw 8 in addition to forming the electrical connection for the grid resistance is also used to retain the spring 9, and to secure the bobbin 1 to the insulator 15 and the plate 6. The hole in 100 the plate 6 which is threaded to receive the screw 8 is made by forcing metal through from one side of the sheet metal from which the plate is pressed in order to form a boss so that as long a thread as possible is obtained. The pin 7 is used to prevent rotation of the bobbin with respect to the insulation 15 as well as to connect the anode 105 resistance winding to the anode plate 5.

For convenience in connecting up appa- 110

ratus in which the device may be fitted the terminals 3 and 4 are placed at right angles to the terminals 12 and 13, as indicated in Fig. 2. Fig. 1 is made a false section as far as the terminals 3 and 4 are concerned for ease of description.

Referring again to Fig. 1, the bobbin 1 has a cover 20 of waterproof material, on which is engraved or printed designations for the terminals 3, 12 and 13, trade marks, data as to electrical values and instructions as to how the device is to be used.

The invention is not limited to the precise arrangements described above and many modifications of details may be made without exceeding the scope of the invention. For example the anode resistance bobbin 1 and the condenser casing 14 may be moulded in one piece of a suitable insulating material, whereby the connecting plates 5 and 6 may be dispensed with, the leads from the lower ends of the resistances being taken through the interior of the casing 14 to the terminals 12 and 13. With this construction the top or outer end of the bobbin may be closed and the tubular cavity may open into the interior of the condenser casing to permit introduction of the resistance 2.

I claim:—
30 1. A coupling device for thermionic

valves comprising a condenser, a casing therefor of insulating material and forming a base member, terminals for said condenser mounted on said base member, a tubular bobbin carried by said base member and having 35 a resistance wound thereon, another resistance accommodated in said tubular bobbin, terminals mounted on the end of the tubular bobbin remote from the base member for one end of each of said resistances, the other 40 ends of said resistances being connected one to each of the terminals for the condenser.

2. In a coupling device for thermionic valves, a condenser, a casing therefor forming a base member, a tubular bobbin carried by said base member and having a resistance wound thereon, and another resistance removably mounted within said bobbin.

3. In a coupling device for thermionic valves, a condenser, a casing surrounding 50 said condenser, a hollow bobbin carried by said casing, a resistance wound on said bobbin, a second resistance mounted within said hollow bobbin, a clip for removably retaining said second resistance in position, and a 55 spring for holding said second resistance in contact with said clip.

In testimony whereof I have signed my name to this specification.

NORMAN LEA.
